COMBINED TWIN BED AND TABLE UNIT

Louis Elliott Frey, Los Angeles, Calif.

Application June 27, 1955, Serial No. 36,692

Term of patent 14 years

(Cl. D15—11)

FIG. 1.

FIG. 2.

Fig. 1 is a front perspective view of a combined twin bed and table unit embodying my new design; and

Fig. 2 is a similar view showing the same with the beds in open position.

I claim:

The ornamental design for a combined twin bed and table unit, substantially as shown.
